INSULATOR CLEVIS

Herbert E. Miller, Allentown, Pa., assignor to
Utilities Service Company, Inc., Allentown, Pa.,
a corporation of Pennsylvania

Application October 6, 1932, Serial No. 636,565

9 Claims. (Cl. 173—366)

This invention relates to insulator clevises.

An important object of the invention is to provide a novel form of clevis for strain insulators which may be quickly and easily attached without the use of special tools.

A further object is to provide a strain insulator clevis employing a flexible cable for surrounding the strain insulator, and to provide novel yoke means carried by the ends of the cable and engageable with each other to maintain a closed loop around the clevis to be attached to suitable supporting means.

A further object is to provide a device of the character referred to wherein a solid member is connected to each end of the flexible cable which surrounds the insulator, and to form the solid members with contacting engaging portions to interlock the two solid members with respect to each other.

A further object is to provide a strain insulator clevis which readily may be placed in position around a strain insulator by virtue of the use of a flexible cable as the insulator embracing means, and to provide solid attaching yoke members on the ends of the flexible cable which may be quickly and easily connected to each other to be engaged by any desired connecting means.

Other objects and advantages of the invention will become apparent during the course of the following description.

In the drawings I have shown several embodiments of the invention. In this showing:

Figure 1 is a side elevation of one form of the device, parts being broken away,

Figure 2 is an edge elevation,

Figure 3 is a plan view,

Figure 4 is a detail inside face view of one of the complementary solid connecting members,

Figure 5 is a side elevation of the same,

Figure 6 is a side elevation of a modified form of the yoke end of the clevis,

Figure 7 is a detail section on line 7—7 of Figure 6,

Figure 8 is a side elevation of a further modified form of the device, a portion of one of the yoke members being broken away,

Figure 9 is a plan view,

Figure 10 is a side elevation of the yoke end of a clevis similar to that shown in Figures 8 and 9 embodying a slight modification,

Figure 11 is a side elevation of a further modified form of the device,

Figure 12 is a plan view of the same,

Figure 13 is a detail section on line 13—13 of Figure 11,

Figure 14 is a side elevation of an additional form of the device,

Figure 15 is a fragmentary side elevation of the same, parts being shown in section, and,

Figure 16 is a detail section on line 16—16 of 5 Figure 15.

Referring to Figures 1 to 5 inclusive, the numeral 10 designates the body of the clevis which is preferably formed of a section of cable preferably formed of individual strands made from copper jacketed ingots drawn down to proper size, and wherein the copper jacketing is applied to the base metal by casting, and without the use of fluxing material. The advantage of the use of such form of cable will become apparent. The cable 10 is adapted to fit around a standard strain insulator (not shown) and assumes substantially the shape shown in Figure 1 when in use forming opposite leg portions connected by a substantially semi-circular central portion 11. The semi-circular portion 11 encircles the end of the insulator, and it will be apparent that the flexibility of the cable permits it to accommodate itself to the shape of the portion of the insulator which it engages, thus preventing the application of pressure at spaced points on the insulator.

The form of the invention shown in Figures 1 to 5 inclusive includes a yoke indicated as a whole by the numeral 12 and made up of complementary sections 13 and 14. These sections, in the form of the invention referred to, have their adjacent faces contacting as at 15 in a plane substantially centrally of the width of the clevis. Each of the yoke members 13 is provided with a downwardly and outwardly extending arm 16 having its end 30 butt welded to one end of the cable section 10. When cable of the character referred to is employed, the ends of the cable may be perfectly butt welded to the ends of the arms 16 to form a perfect joint which has been found in actual practice 35 to withstand great strains without cracking or breaking, and the absence of fluxing in the cable material prevents corrosion or other destruction of the cable adjacent the bonding point.

Each of the members 13 and 14 is provided 40 with an upstanding projection 17 coacting to form a circular shank screw threaded for reception in a nut 18. The upper extremities of the body portions of the members 13 and 14 form a shoulder 19 upon which the nut 18 is seated 45 when the device is assembled.

Referring to Figures 4 and 5 it will be noted that the contacting faces 15 of the yoke members are provided with interlocking means to prevent relative sliding movement of the con- 55

tacting faces of the yoke members when the latter are brought into engagement. In order that a single die may be employed for forming the members 13 and 14, the die is adapted to form each member with an outstanding lug preferably of circular cross section. After the member is completed half of each lug is cut away as at 20, thus leaving a semi-circular outstanding lug 21. The face 15 is then punched inwardly in alignment with the portion of the lug which has been cut away to form a recess 22 which also is semi-circular in shape. It will be apparent that the lugs of one of the members is cut away at one side while the lug of the other member is cut away at the opposite side, and accordingly the semi-circular lug of each member is adapted to be received in the semi-circular recess of the other member. With the faces of the members 13 and 14 brought together, it will be apparent that the inter-engagement of the lug elements 21 and sockets or recesses 22 prevents relative sliding movement of the members 13 and 14.

A slightly modified form of the invention is shown in Figures 6 and 7 in which the yoke element alone has been illustrated. Such element is designated as a whole by the numeral 23 and comprises complementary sections 24 and 25 having arm portions 26 to which the ends of the cable section are adapted to be butt welded. Instead of the yoke being completely divided on a transverse plane, the central portion of the yoke is divided on a plane formed by the contacting faces 27 of the yoke members, such plane being coincident with the plane of the clevis. The yoke is further split transversely on opposite sides of the center thereof as at 28 to form the separate sections.

The yoke 23 also is provided with an upstanding threaded portion 29 adapted to be received in a nut 30. The projecting portion 29 is split in the plane of the faces 27. Preferably within the limits of the threaded portion 29, each member 24 and 25 is provided with an outstanding lug 31 engageable in a recess 32 in the other member. This arrangement permits the members 24 and 25 to be made identical with each other thus requiring the use of only a single die.

The form of the invention shown in Figures 8 and 9 is somewhat different from the forms previously described, but retains the essential feature of providing solid yoke members carried by the ends of the cable and engageable with each other. This form of the invention does not require the use of any fastening elements and is wholly self-contained. Referring to Figure 8, the numeral 33 designates a cable section similar to the section 10 previously described. A yoke indicated as a whole by the numeral 34 is formed of sections 35 and 36 each of which has an arm portion 37 the ends of which are adapted to be butt welded to the ends of the cable section 33. The section 35 is provided with an upstanding tapered extension 38 formed integral therewith, while the section 36 is provided with an integral ring or eye 39 having a tapered opening 40 to receive the projection 38.

The engagement of the projection 38 and eye 39 is sufficient to retain the elements in position when the insulator is subjected to the usual strain. It is preferred however, that means be provided to positively prevent relative rotating action between the projection 38 and eye 39. Accordingly the member 36 is provided with a re-

cess 41 receiving a lug 42 formed integral with the yoke member 35.

The form of the invention shown in Figure 10 is identical with the form shown in Figures 8 and 9 except for a slight modification, and need not be referred to in detail. It is sometimes desirable to connect a strain insulator clevis to a solid fixed support having a threaded opening therein, and for this purpose, the device shown in Figure 10 is provided with a threaded extension 10 43 preferably formed integral with the tapered extension 38.

In the form of the invention shown in Figures 8 and 9, relative movement of the yoke members axially of the device is prevented by reception of the projection 38 in the opening 40. In the form of the invention shown in Figures 11 and 12, such relative movement is prevented by interfitting formations on the contacting faces of the yoke members, and movement of such members laterally away from each other is prevented by the eye or similar means to which the yoke is connected. Referring to Figure 11 the numeral 44 designates the cable section forming a part of the device and similar to the cable 25 section previously described. A yoke member indicated as a whole by the numeral 45 is formed of complementary sections 46 and 47. These sections have their body portions identical in shape with each other each having an arm portion 48 adapted to be butt welded to one end of the cable section 44.

Each of the sections is recessed as at 49 whereby the ends of the sections are relatively offset for interfitting engagement with each other. The recess forms the two sections with parallel faces contacting with each other, one of these faces being provided with outstanding lugs 50 and the other with recesses 51 to receive the lugs. The extremities of the recesses 49 of the two members 40 obviously closely fit against each other as indicated by the numeral 52. Referring to Figure 12, it will be noted that the central portion of the yoke 45 is materially thickened to increase the inherent strength of the yoke and to render such central portion thereof engageable with the eye to which it is connected whereby such eye prevents movement of the yoke members 46 and 47 away from each other.

In Figures 14 and 15, the yoke is indicated as a whole by the numeral 53 and comprises sections 54 and 55 terminating in arm portions butt welded to the ends of a cable section 56. The section 54 is materially longer than the section 55 and includes a curved portion 57 forming the extremity of the clevis and adapted for connection with suitable eye or other supporting means. Accordingly the two sections are connected at one side of the center of the clevis. Referring to Figure 15, it will be noted that each section has its adjacent end recessed as at 58 and each section has its portion at the end of the recess projecting inwardly as at 59. Obviously, the projection 59 of each yoke member engages within the recess 58 of the other member. Thus an interfitting connection is provided between the two yoke sections, and the latter have their ends in axial alignment with each other.

At a point spaced from the adjacent end of the yoke section 54, the section 55 is reduced in size to form an annular shoulder 60. A sleeve 61 is adapted to surround the interlocking portions of the two yoke members and is provided with an inwardly extending annular flange 62 at its lower end engageable with the shoulder 60.

A cotter pin 63 is adapted to prevent downward movement of the sleeve 61 when the latter is in operative position.

The operation of the form of the invention shown in Figures 1 to 5 inclusive is as follows: With the nut 18 removed from the device, the flexibility of the cable permits the yoke sections 13 and 14 to be spread apart whereupon the strain insulator may be arranged in position within the flexible cable 10. The device is then placed in position with respect to the connecting means employed therewith, such as an eye arranged within the yoke. The two yoke members are then brought into operative engagement with each other with the lugs 21 arranged in the recesses 22, whereupon the nut 18 is threaded on the complementary projections 17. The device is then completely assembled. It will be apparent that the engagement of the nut 18 with the shoulder 19 effectually provides bracing means for the two yoke members to positively prevent spreading thereof incident to the application of force in alignment with the contacting faces 15. Accordingly the device is sturdy in operation, and may be subjected to great and sustained strains without any loosening of the parts. It will be apparent that the device readily may be assembled without the use of special tools.

The operation of the form of the device shown in Figures 6 and 7 is identical with that previously described except that the yoke members are moved laterally to separate them to permit the insulator to be arranged in position. The recessing of the yoke members at offset points as indicated by the numeral 28 provides each yoke member with a portion extending over the line of pull of the member to which the yoke is connected, and accordingly any tendency of the yoke members to spread is prevented. Moreover, this construction permits the two yoke members to be identical in shape, thus requiring only a single die in forging the device. In the forms of the device shown in Figures 8, 9, and 10, no fastening means whatever is required for holding the yoke members in cooperative relationship. When the device is not subjected to a longitudinal strain, the flexibility of the cable section 33 readily permits separation of the yoke members to permit assembly of the device. Once the device has been assembled the longitudinal pull exerted upon the yoke holds the projection 38 within the eye 39 thus positively preventing displacement of the parts. The use of the lug 42 is not essential, but is preferred to prevent rotation of the parts about the axis of the projection 38, and accordingly no relative movement of the yoke members is permitted when the device is in use. The projection 38 may be provided with the threaded extension 43 to permit the device to be connected to a fixed support having a threaded opening therein. The extension 43 is not sufficiently long to prevent removal of the eye member 39 in assembling and disassembling the device.

In the form shown in Figures 11, 12, and 13, it merely is necessary to move the yoke members laterally to separate the lug 50 from the recesses 51 whereupon the yoke members may be pulled apart to permit the insulator to be placed in position therein. When the device is assembled, the lugs 50 serve to positively prevent relative movement of the yoke members in the plane of the clevis, although it will be apparent that no appreciable movement of this character can take place in view of the fact that the inner ends

of the yoke members extend beyond the line of pull. An attaching eye passing around the center of the yoke prevents lateral separation of the yoke members since its curvature causes it to embrace such members to a sufficient extent to prevent the lateral separating movement referred to. 5

In the form of the invention shown in Figures 14, 15, and 16, the sleeve 51 is normally moved downwardly from the position shown in Figure 10, and accordingly the yoke members are free to be separated by virtue of the flexibility of the cable section 56. After the device is assembled the sleeve 61 is moved upwardly to bring the flange 62 into engagement with the shoulder 60, 15 whereupon the cotter pin 63 is inserted and the parts are positively locked together.

It will be apparent that each form of yoke has its upper inner extremity curved for proper engagement with an eye or similar attaching means. 20 Each of the forms of the invention moreover embodies a two-piece yoke with the elements secured to the respective ends of a cable member. The yoke members are provided with interfitting portions which fix the relationship between such 25 elements. The use of the cable is advantageous in that its flexibility permits ready assembly of the device, and the use of the particular kind of cable referred to permits a highly efficient and permanent bonding between the ends of the cable 30 and the yoke elements. Each form of the device is characterized by its simplicity and minimum number of parts whereby it may be economically manufactured. Each form of the device is capable of being assembled more easily and quickly 35 than has been possible with the forms of insulator clevises heretofore developed. The yoke members preferably are formed of forged steel suitably galvanized or otherwise coated to protect them from the weather. 40

It is to be understood that the forms of the invention herewith shown and described are to be taken as preferred examples of the same and that various changes in the shape, size and arrangement of parts may be resorted to without departing from the spirit of the invention or the scope of the subjoined claims. 45

I claim:

1. A strain insulator clevis comprising a body formed of a flexible metallic member adapted to 50 assume an elongated operative shape around a strain insulator, and a yoke comprising complementary separable members each secured to one end of said metallic member, one of said members having an eye formed integral therewith and the other terminating in a stud frictionally engageable in said eye, at least one of said complementary members being arranged at one end of said body when the latter is in operative shape to form a bearing element. 55

2. A strain insulator clevis comprising a body formed of a flexible metallic member adapted to assume an elongated operative shape around a strain insulator, and a yoke comprising complementary separable members each secured to one end of said metallic member, one of said complementary members terminating in a stud projecting longitudinally of the clevis outwardly thereof, the other complementary member having an integral eye frictionally receiving said stud, at least one of said complementary members being arranged at one end of said body when the latter is in operative shape to form a bearing element. 65

3. A device constructed in accordance with claim 2 wherein said stud and the opening in said 70 75

eye are tapered to decrease in diameter outwardly with respect to the clevis.

4. A strain insulator clevis comprising a body formed of a flexible metallic member adapted to assume an elongated operative shape around a strain insulator, and a yoke comprising complementary separable members each terminating at one end in an arm butt welded to one end of said flexible member, the other end of one complementary member terminating in an eye and the other terminating in a stud frictionally engageable in said eye, at least one of said complementary members being arranged at one end of said body when the latter is in operative shape to form a bearing element.

5. A strain insulator clevis comprising a body formed of a flexible metallic member adapted to assume an elongated operative shape around a strain insulator, and a yoke comprising complementary separable members each terminating at one end in an arm butt welded to one end of said flexible member, the other end of one complementary member terminating in an eye and the other terminating in a stud frictionally engageable in said eye, said stud extending in a direction away from said flexible member and tapered to decrease in diameter toward its extremity, at least one of said complementary members being arranged at one end of said body when the latter is in operative shape to form a bearing element.

6. A strain insulator clevis comprising a body formed of a flexible metallic member looped intermediate its ends to assume an elongated operative shape around a strain insulator, and a yoke comprising complementary separable members each secured in end to end relation to one end of said flexible member, said complementary members having portions interlockable upon movement of one of such members in a direction away from the loop in said flexible member, said last named complementary member having an inner bearing portion facing in the direction of the loop in said flexible member and extending across a plane which passes through the line of pull on the clevis and which is at right angles to the plane of said flexible member.

7. A strain insulator clevis comprising a body formed of a flexible metallic member looped intermediate its ends to assume an elongated oper-

ative shape around a strain insulator, and a yoke comprising complementary separable members each secured to one end of said flexible member, one of said complementary members being provided with an eye and the other with a stud engageable in said eye and having its axis arranged substantially parallel to the line of pull on the clevis, said last named member having an inner bearing portion facing in the direction of the loop in said flexible member and extending across a plane which passes through the line of pull on the clevis and which is at right angles to the plane of said flexible member.

8. A strain insulator clevis comprising a body formed of a flexible metallic member looped intermediate its ends to assume an elongated operative shape around a strain insulator, and a yoke comprising complementary separable members each secured in end to end relation to one end of said flexible member, said complementary members having portions interlockable upon movement of one of such members in a direction away from the loop in said flexible member, said last named complementary member having an inner bearing portion facing in the direction of the loop in said flexible member and extending across a plane which passes through the line of pull on the clevis and which is at right angles to the plane of said flexible member, the ends of said complementary members which are secured to the ends of said flexible member being spaced apart a distance substantially less than the normal width of the clevis.

9. A strain insulator clevis comprising a body formed of a flexible metallic member looped intermediate its ends to assume an elongated operative shape around a strain insulator, and a yoke comprising complementary separable members each secured in end to end relation to one end of said flexible member, one of said complementary members having an inner bearing portion facing in the direction of the loop in said flexible member and extending across the line of pull on the clevis, said last named complementary member being movable away from the loop in said flexible member in a line coincident with the line of pull on said clevis into interlocking relationship with the other complementary member.

HERBERT E. MILLER.
